UNITED STATES PATENT OFFICE.

GLENN H. CURTISS, OF HAMMONDSPORT, NEW YORK.

FLYING-MACHINE.

1,108,490.

Specification of Letters Patent. Patented Aug. 25, 1914.

Application filed January 28, 1913. Serial No. 744,626.

To all whom it may concern:

Be it known that I, GLENN H. CURTISS, a citizen of the United States, residing at Hammondsport, New York, have invented 5 certain new and useful Improvements in Flying-Machines, of which the following is a clear, full, and exact description.

This invention relates to improvements in heavier-than-air flying machines more particularly of the hydro-aeroplane type, although it may be also advantageously employed in connection with other machines.

Flying machines when at rest are often exposed to side winds which may cause a 15 lifting pressure beneath the lateral portions of the main supporting planes at the windward side of the machine and either turn over the machine or bring about undesirable strains on the parts.

20 The use of the present improvement will, in a large part, obviate the objectionable effects of side winds as will be clear from the full understanding of the invention herein-after described.

25 It is to be understood that the present improvement may be applied to any of the well-known types of aeroplanes now on the market, such as the Curtiss or Wright machines, and in illustrating my preferred embodiment thereof, I have shown in the figures of the drawings merely sufficient structure for the complete understanding of the present invention, omitting disclosure of other well-known parts of such machines 30 which are necessary to make up a complete flying machine.

The following specification will give a clear understanding of the invention, and the scope thereof will be set forth in the appended claims.

Figure 1 is a front elevation of a hydro-aeroplane of the biplane type, with a portion of my improvement thereon; Fig. 2 is an enlarged detail of one end of the same; 45 Fig. 3 is a plan of the structure shown in Fig. 2; Fig. 4 is an enlarged front elevation of a modification showing certain additional features of the invention; Fig. 5 is a diagram illustrating the connections which lead 50 from the operator's control to the adjustable parts of the present improvement.

Referring first to Fig. 1, the upper and lower main supporting aeroplane surfaces of the machine are indicated at 1 and 2, con-

nected by the usual struts 3. Central float 55 means such as the boat 4 is located below the supporting planes at substantially the transverse center of the machine. This central floating means is preferably of sufficient buoyancy to completely sustain the machine 60 on the water and forms the main support therefor, although material assistance may be given at times by side float bodies herein-after described. It is well understood that in this hydro-aeroplane type of machine, the 65 operator's seat and controls are located within or adjacent to this central floating means. At each side of the machine I have provided lateral surfaces which may be either auxiliary to the main supporting aeroplane surfaces or the main supporting surfaces themselves, movable to present angles of incidence negative at the windward side and positive at the leeward side to a relatively 70 side wind coming toward the machine. In the embodiment shown in Fig. 1, these movable surfaces consists of small auxiliary planes 5 and 7 pivoted adjacent the opposite extremities of the upper aeroplane surface 1 by suitable hinges such as 6 and 8 75 forming in this case extensions of said aeroplane surface. The inner or abutting edge of the auxiliary planes 5 and 7 are preferably as wide as the adjacent outer edge of the aeroplane surface 1, although these auxiliary planes 5 and 7 may converge to a narrower outer edge as shown in Fig. 3. Each of the hinged planes 5 and 7 may be suitably supported in position by struts 9 and 11, pivotally connected at one end as at 37 and 80 38, to the planes and having a slidable connection at the other end through suitable loops such as 10 and 12 fixed on the machine. These hinged planes 5 and 7 are 85 preferably adjusted to different positions by means of suitable connecting cables 13 and 14 running therefrom to the operator's control or lever 15 pivoted at 16 adjacent the operator's seat. This lever 15 is provided with a suitable detent 19, co-operating with 90 a notched rack 19^a for fixed adjustment in different positions. It will be clear from the drawings that a cable 13 fixed to the upper portion of the lever 15 at 17 leads to the lower end of one strut such as 9, and to the 95 upper portion of the other strut 11, whereas cable 14 fixed to the lower end of lever 15 at 18 leads to the upper portion of strut 9 and

to the lower portion of strut 11. Suitable guides such as 20 and 21 may be provided at the corners of the machine for guiding the cables in the proper direction as shown in Fig. 2.

It will be obvious from the foregoing that the lever 15 when thrown to the left, looking at Fig. 1, will by means of cable 13 elevate the plane 5 and by cable 14 elevate the plane 7 to the normal position shown, whereby these planes form horizontal extensions of the main aeroplane surface. Likewise, when lever 15 is thrown to the right, cables 13 and 14 will swing both of the auxiliary planes 5 and 7 downwardly in an angular relation to the main aeroplane surface 1 so as to present a negative angle of incidence to any wind which may come toward its respective side of the machine. In this way a depressing effect at the windward side of the machine may be caused by a side wind rather than a lifting effect, and thus prevent the machine when at rest, from being turned over or damaged by side gusts.

So far those features of the present improvement which relate merely to the movable lateral surfaces have been described. I also contemplate the use in a hydro-aeroplane machine of side floats either with or without the lateral surfaces, which side floats are to be bodily movable up and down with respect to the central floating means or boat 4, so as to either rest upon the water simultaneously with said boat 4 for trimming said machine on the water in lateral equilibrium, or to be raised into a higher position for clearing the water, while the boat 4 is still in contact therewith.

Referring more particularly to Fig. 4, it will be observed that in addition to the lateral movable surfaces 5^a 7^a mounted adjacent the lateral extremities of the upper aeroplane surface 1, there are provided float bodies 21 and 51, one at each side of the machine below the aeroplane surfaces and adjacent the extremities thereof. As both of these float bodies are similarly mounted, a description of one will suffice. The float body itself may be of any suitable shape preferably conforming to stream line requirements and although buoyant for sustaining its respective end of the machine when required, need not necessarily be of the same buoyant capacity as the central floating means 4. In the present embodiment, each side floating body such as 21 is a hollow air filled elongated tank, mounted so as to incline downwardly from front to rear and preferably formed with a hydro surface at its lower side and having a water blade 34 extending from its rear end toward the water so as to first engage therewith when one side or the other of the machine is depressed. The side float or tank 21 in the modification shown in Fig. 4, is mov-

ably mounted upon the machine by means of a parallel link mechanism so as to have a substantially vertical parallel movement. The outer links 22 are pivotally connected at one end 26 to the float and connected at their other ends to sleeves 25 slidably mounted upon side struts 9 of the machine. The links 23 may be fixed to the float at one end and pivoted at 24 to the lower aeroplane surface, whereby the float may swing bodily in various parallel positions up and down with respect to the machine. In this modification the movable lateral surfaces 5^a, 7^a, are similarly mounted and moved as was described in connection with Fig. 1, and adjacent the operator's seat are located two control levers 19 and 40, one for operating both lateral surfaces 5^a 7^a in the same direction simultaneously, and the other lever for operating both floats 21 and 51 simultaneously up and down.

In Fig. 4 is shown a cable 27 leading from the upper end of lever 40 over a guide and downwardly to a connection with the float structure 21, and cable 27^a is shown leading from the lower part of lever 40 over a guide and downwardly to a connection with float 51. Cable 28 leads from the lower part of lever 40 around the guide 20 and upwardly to a connection with the float 21 such as sleeve 25, and cable 28^a leads from the upper part of lever 40 around a guide 21 upwardly to a connection with float 51 such as sleeve 25^a. It will be noted from this view as well as from the diagram Fig. 5, that the connections are so arranged that by throwing lever 40 to the left, a pull on cables 27 and 27^a is brought about to elevate the floats 21 and 51, whereas throwing lever 40 to the right causes a pull on cables 28 and 28^a which will lower the floats 21 and 51. In a similar manner cables 13 and 13^a connected to opposite ends of lever 19 lead to lower ends of the struts 9 and 11 respectively, while cables 14 and 14^a connected to opposite ends of the same lever 19 lead to upper ends of struts 9 and 11 respectively, whereby a pull on cables 13 and 13^a will elevate the planes 5^a and 7^a, and a pull on cables 14 and 14^a will incline the same as shown in dotted lines Fig. 4.

It will be understood that the present description of the drawings specify certain forms in which my invention may be embodied, and that further forms and modifications are embraced in the full scope of my invention as expressed in the appended claims.

What I claim is:

1. In a heavier-than-air flying machine in combination, a main plane fixed in position, a central floating device located below the longitudinal axis of the machine and adapted to support said entire machine upon the

- water, adjustable auxiliary planes pivoted at the lateral edges of said main plane and adapted to swing about longitudinal axes to present inclined surfaces to a current of air 5 coming toward the side of the machine, and auxiliary float members spaced from said central floating device and mounted at each side of the machine substantially beneath said auxiliary planes for supporting from the water that portion of the machine carrying the auxiliary planes, said float members being adjustable bodily up and down for trimming the machine upon the water in lateral equilibrium.
- 10 2. In a heavier-than-air flying machine in combination, a main plane fixed in position, a central floating device located below the longitudinal axis of the machine and adapted to support said entire machine upon the water, adjustable auxiliary planes pivoted at the lateral edges of said main plane and adapted to swing about longitudinal axes to present inclined surfaces to a current of air coming toward the side of the machine, 20 auxiliary float members spaced from said central floating device and mounted at each side of the machine substantially beneath said auxiliary planes for supporting from the water that portion of the machine carrying the auxiliary planes, said float members being adjustable bodily up and down for trimming the machine upon the water in lateral equilibrium, and manually controlled means for independently adjusting said auxiliary planes or said auxiliary floats.
- 25 3. In a heavier-than-air flying machine in combination, laterally extending planes each pivotally mounted for adjustable movement about longitudinal axes, manually controlled means for adjusting said planes simultaneously to equal angles in the same direction up or down, a central floating device for supporting said entire machine upon the water, and auxiliary float members spaced from said central floating device and mounted at each side of said machine substantially beneath the lateral ends of said planes for supporting the same from the water, said auxiliary float members being 35 adjustable bodily up and down for trimming the machine upon the water in lateral equilibrium.
- 40 4. In a heavier-than-air flying machine in combination, laterally extending planes pivotally mounted for adjustable movement about longitudinal axes, manually controlled means comprising a single hand-lever for adjusting said planes simultaneously to equal angles in the same direction up or 45 down, a central floating device for supporting said entire machine upon the water, auxiliary float members spaced from said central floating device and mounted at each side of said machine substantially beneath 50 the lateral ends of said planes for support-
- ing the same from the water, said auxiliary float members being adjustable bodily up and down for trimming the machine upon the water in lateral equilibrium.
5. In a heavier-than-air flying machine 70 in combination, a main plane, adjustable auxiliary planes pivoted at the lateral edges of said main plane for movement up and down about longitudinal axes, supporting struts connected to said movable auxiliary planes and guided for slidable movement on said machine, an operator's controlling lever, and connections from said lever to said struts for swinging said auxiliary planes simultaneously in the same direction up or down when said lever is moved.
6. In a heavier-than-air flying machine in combination, superposed main planes fixed in position, adjustable auxiliary planes pivoted at the lateral edges of an upper main plane for movement about longitudinal axes, supporting struts connected to said movable auxiliary planes, and guided for slidable movement through the lower plane of said machine, an operator's controlling lever, and connections from said lever to said struts for moving the same simultaneously in the same direction up or down when said lever is moved.
7. In a heavier-than-air flying machine in 95 combination, superposed main planes, adjustable auxiliary planes pivoted at the lateral edges of an upper main plane to swing about longitudinal axes, supporting struts slidably connected to said lower plane for an up and down movement therethrough, and pivotally connected to said movable auxiliary planes.
8. In a heavier-than-air flying machine in 100 combination, superposed main planes fixed in position, adjustable auxiliary planes pivoted at the lateral edges of an upper main plane for movement about longitudinal axes, supporting struts slidably guided on said lower plane and pivotally connected to said movable auxiliary planes, an operator's controlling lever and flexible cable connections from said lever to said struts for swinging said auxiliary planes simultaneously in the same direction up or down 115 when said lever is moved.
9. In a heavier-than-air flying machine in 120 combination, a main plane, adjustable auxiliary planes pivoted at the lateral edges of said main plane, supporting struts connected to said movable auxiliary planes and guided for slidable movement on said machine, auxiliary float members mounted at each side of said machine and connected with said struts for supporting the lateral ends 125 of the machine from the water.
10. In a heavier-than-air flying machine in combination, a main plane, adjustable auxiliary planes pivoted at the lateral edges of said main plane, supporting struts con- 130

ected to said movable auxiliary planes and guided for slideable movement on said machine, auxiliary float members mounted at each side of said machine and having sliding connections with said struts for supporting the lateral ends of the machine from the water, and manually controlling means for independently adjusting said auxiliary

planes and said auxiliary floats to different positions. 10

GLENN H. CURTISS.

Witnesses:

G. V. MADISON,
A. THOMSON.

It is hereby certified that in Letters Patent No. 1,108,490, granted August 25, 1914, upon the application of Glenn H. Curtiss, of Hammondsport, New York, for an improvement in "Flying-Machines," errors appear in the printed specification requiring correction as follows: Page 1, line 77, for the word "consists" read *consist*; page 2, line 16, for the word "an" read *in*; and that the said Letters Patent should be read with these corrections therein that the same may conform to the record of the case in the Patent Office.

Signed and sealed this 22d day of September, A. D., 1914.

[SEAL.]

R. F. WHITEHEAD,

Acting Commissioner of Patents.
